(57) **CLAIM**

The ornamental design for an electric bicycle as shown and described.

DESCRIPTION

FIG. 1 is a top, front and left side perspective view of an electric bicycle showing our new design;

FIG. 2 is a bottom, rear and right side perspective view thereof;

FIG. 3 is a left side elevation view thereof;

FIG. 4 is a right side elevation view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is an enlarged detail view taken from the encircled area 9 of FIG. 1;

FIG. 10 is an enlarged detail view taken from the encircled area 10 of FIG. 1;

FIG. 11 is an enlarged detail view taken from the encircled area 11 of FIG. 1;

FIG. 12 is an enlarged detail view taken from the encircled area 12 of FIG. 2;

FIG. 13 is an enlarged detail view taken from the encircled area 13 of FIG. 2;

FIG. 14 is an enlarged detail view taken from the encircled area 14 of FIG. 2;

FIG. 15 is an enlarged detail view taken from the encircled area 15 of FIG. 2;

FIG. 16 is an enlarged detail view taken from the encircled area 16 of FIG. 3;

FIG. 17 is an enlarged detail view taken from the encircled area 17 of FIG. 3;

(Continued)

FIG. 18 is an enlarged detail view taken from the encircled area 18 of FIG. 4;

FIG. 19 is an enlarged detail view taken from the encircled area 19 of FIG. 5;

FIG. 20 is an enlarged detail view taken from the encircled area 20 of FIG. 5;

FIG. 21 is an enlarged detail view taken from the encircled area 21 of FIG. 6;

FIG. 22 is an enlarged detail view taken from the encircled area 22 of FIG. 6; and,

FIG. 23 is an enlarged detail view taken from the encircled area 23 of FIG. 8.

The dot-dash lines are provided for annotative purposes only to show the areas of enlargements. The dot-dash lines do not illustrate structures or subject matters and do not form part of the claimed design.

The broken lines in the drawing depict portions of the electric bicycle that form no part of the claimed design.

1 Claim, 23 Drawing Sheets
